UNITED STATES PATENT OFFICE.

HERBERT H. METZGAR, OF LOS ANGELES, CALIFORNIA.

DESIGN FOR A CUSHION STOOL.

Application filed December 15, 1927. Serial No. 24,492. Term of patent 14 years.

To all whom it may concern:

Be it known that I, HERBERT H. METZGAR, a citizen of the United States, residing at Los Angeles, in the county of Los Angeles and State of California, have invented a new, original, and ornamental Design for Cushion Stools, of which the following is a specification, reference being had to the accompanying drawing, forming part thereof.

The figure is a perspective view of a cushion stool showing my new design.

I claim:

The ornamental design for a cushion stool, as shown.

H. H. METZGAR.
